(57) **CLAIM**

The ornamental design for an electric vaporizer, as shown and described herein.

DESCRIPTION

FIG. 1 is a perspective view of my electric vaporizer in accordance with my invention;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken line portions of the figure drawings are included to show portions of the article that form no part of the claimed design.
